(57) **CLAIM**

The ornamental design for an information display for vehicle, as shown and described.

DESCRIPTION

FIG. 1 is a perspective view of the front, right, and top side of an information display for vehicle showing a first embodiment of our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the front, right, and top side of an information display for vehicle showing a second embodiment of our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines represent portions of the information display for vehicle which form no part of the claimed design. The dash-dot lines represent boundaries and form no part of the claimed design.

1 Claim, 14 Drawing Sheets
